Primary Examiner — Lauren D McVey*Assistant Examiner* — Justin A Johnson(57) **CLAIM**

The ornamental design for light strip for mirror, as shown and described.

DESCRIPTION

FIG. 1 is a perspective view of a light strip for mirror showing my new design according to a first embodiment; FIG. 2 is a front elevation view thereof; FIG. 3 is a back elevation view thereof; FIG. 4 is a left side elevation view thereof; FIG. 5 is a right side elevation view thereof; FIG. 6 is a top plan view thereof; and FIG. 7 is a bottom plan view thereof.

FIG. 8 is a perspective view of a light strip for mirror according to a second embodiment;

FIG. 9 is a front elevation view thereof;

FIG. 10 is a back elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The broken lines immediately adjacent to the shaded areas depict the bounds of the claimed design, while all other broken lines are directed to environment. The broken lines form no part of the claimed design.
